ABSTRACT OF THE DISCLOSURE

The lower alkyl or benzyl esters and amides of the N-monoacyl derivatives of the basic amino acids (α, γ -diaminobutyric acid, ornithine, citrulline, lysine, arginine, and histidine) and their N-methyl and N-benzyl derivatives in which acyl is the acyl radical of an aliphatic monocarboxylic acid having 6 to 20 carbon atoms have bacteriostatic effects of the order of magnitude of that of hexachlorophene. They may be used as antibacterial agents in the form of their water soluble salts with hydrochloric acid, pyrrolidone carboxylic acid, and other inorganic and organic acids.

This application is a continuation-in-part of the copending application Ser. No. 99,768, filed on Dec. 21, 1970 and now abandoned.

This invention relates to antiseptic, disinfectant, medicinal, preservative, bactericidal, bacteriostatic, germicidal and fungicidal materials and compositions.

Corrosive sublimate, cresol, alcohol, invert soap and etc. have been used as disinfectants or antimicrobial detergents in food hygienic field, environment sanitary field and medicinal field. However, these disinfectants have the following unsatisfactory properties. Corrosive sublimate has powerful disinfectant action, but it has a strong irritation against skin and causes a serious problem in the disposal of waste matters owing to mercury containing material. And cresol has high toxicity to men and beasts, while alcohol has weak disinfectant action. Although invert soap such as "Hyamine" (Product of Rohm & Haas Co., Inc.) has a powerful disinfectant action, the effect is markedly decreased by co-existence of protein, fat, sodium chloride, or soap, and it has high toxicity to men and beasts (For example, the acute oral toxicity (LD_{50}) value of "Hyamine" is 420 ± 25 mg. per kg. of body weight of mice.)

Recently, a disinfectant incorporating soap or synthetic detergent, the so-called deodorant detergent is recommended. As disinfectants or deodorizers in these detergents, for example hexachlorophene, trichlorocarbanilide, tribromosalicyanilide, tetramethylthiuram disulfide and the like have been practically used. However, each of these deodorizers has irritation of the skin and is hardly soluble or insoluble in water, and hence it is necessary that these deodorizers are incorporated in a relatively large amount into detergent for purpose to retain their antimicrobial activity. And the use of such a large amount causes further strong irritation on the skin. Particularly, hexachlorophene or tetramethylthiuram disulfide incorporating detergent has been reported to cause eczematid, sensitization to the skin when exposed to sunlight after its use. Also, usual cationic surfactants which exhibit in general strong antimicrobial action are water soluble, but they cannot be used as deodorizers of detergents, since an insoluble precipitation is formed when they are incorporated in deter-

gent such as soap and thereby antibacterial activity is reduced or disappeared as well as the detergency is markedly reduced.

On the other hand, cosmetics, leather goods, rubber goods, paints, foods and feed are easily attacked and deteriorated by microorganism and hence almost all of them does not stand long storage or use.

Various antiseptic agents or antifungal agents have been hitherto developed and employed in this field. However, there has not yet been proposed antiseptic agent which possesses low or non-toxicity, non-irritation in addition to the complete inhibition of the growth of microorganisms. For example, since cosmetics are composed mainly of water and oil and since they also contain glycerin, protein and other materials which are easily attacked by microorganisms, they are able to be changed in quality and appearance as well as foods. Hence, benzoic acid, its derivatives hexachlorophene and the like have been employed as antiseptic agent for cosmetics, but all of them have the following disadvantages: (1) The concentration in water phase which is easily attacked by microorganisms is low because of their oil-soluble properties. (2) Their antiseptic effect is greatly reduced by the action of surface active agents which are present in cosmetics. (3) They have skin-irritation and high toxicity.

In addition, sorbic acid, sodium propionate, dehydroacetic acid, nitrofuran series compounds and etc. have been used as antiseptic agents for food but the amount added of them is restricted from the standpoint of toxicity and so, they can not exert sufficient antiseptic effect within their allowance of addition. Recently, higher alkyl derivatives of peptide containing glutamic acid or basic amino acid have been used as antiseptic agents, but the former is hard to handle because of its very low water solubility, whereas the latter injures the taste of food because of very bitter taste in addition to high cost.

An object of the present invention is to provide deodorizers which are suitable to be incorporated into a detergent and which have the desired characteristic properties in that they exert excellent antimicrobial action, cause no irritation to the skin and are effective to enhance cleaning effect.

It is another object of the present invention to provide an antiseptic material composition in which the disadvantages of the known antiseptic materials are reduced or obviated.

It has been found that mono-N-higher aliphatic acyl basic amino acid derivatives of α, γ -diaminobutyric acid, arginine, ornithine, citrulline, lysine and histidine, and salts thereof, hereinafter described in detail, have the desirable and satisfactory characteristic property as deodorizers of detergents, owing to their water soluble property, their excellent antimicrobial activity against microorganisms such as bacteria and fungi, their good surface active action and their mildness to the skin. Moreover, by the use of them, skin troubles such as irritation of the skin, eczematid and sensitization are not entirely recognized, and even when incorporated in soap and other synthetic detergents, they greatly exert their excellent antimicrobial action without reducing cleaning effect. Also, in case where they are incorporated in synthetic detergents which usually roughen the skin, they have skin protecting action preventing the skin from chapping.

It has further been found that said mono-N-higher aliphatic basic amino acid derivatives antiseptic, medicinal, preservative, bactericidal, bacteriostatic, germicidal and fungicidal properties.

According to the present invention, there are provided antiseptic, disinfectant, medicinal, preservative, bactericidal, bacteriostatic, germicidal and fungicidal agents which are much secure to men and beasts, comprising at least one mono-N-higher aliphatic acyl basic amino acid derivatives

having the following general formula (I), (II) and (III), and salts thereof:

Wherein RCO is a saturated or unsaturated fatty acid radical containing from 6 to 20 carbon atoms, R_1 is H or $-\text{CH}_3$, X is $-\text{NH}_2$, $-\text{OCH}_3$, $-\text{OC}_2\text{H}_5$, $-\text{OC}_3\text{H}_7$, $-\text{OC}_4\text{H}_9$

or $-\text{OCH}_2\text{C}_6\text{H}_5$, R_2 is H or $-\text{CH}_3$, R_3 is H , $-\text{CH}_3$ or $-\text{CH}_2\text{C}_6\text{H}_5$, R_4 is

and n is 1, 2, 3 or 4.

Compounds which are incorporated as deodorizers in detergent and which are also useful as antiseptic material or germicide according to the present invention may be easily prepared and are cheaply available. That is, among the compounds of the general formulas (I) and (II), ones wherein n is 2 are α - γ -diaminobutyric acid derivatives, ones wherein n is 3 are ornithine derivatives and ones wherein n is 4 are lysine derivatives. And, the compounds of general formula (III) are arginine, citrulline and histidine derivatives. Each of these mono-N-higher acyl basic amino acid derivatives may be easily prepared by the reaction of corresponding basic amino acid with higher fatty acid chloride in alkaline aqueous medium.

Either of optically active L- or D-form or racemic form of basic amino acid components are effective.

As salts of these N-higher aliphatic acyl basic amino acid derivatives, for example mineral acid salts such as hydrochloride and sulfate, salts with organic acid such as an optically active or inactive α -pyrrolidonecarboxylic acid, an optically active or inactive acidic amino acids (e.g. glutamic acid and aspartic acid), lactic acid, citric acid and acetic acid are taken. Especially, the use of hydrochloride and salt with DL- or L- α -pyrrolidonecarboxylic acid are suitable from a point of view of crystalline nature.

Representative examples of mono-N-higher aliphatic acyl basic amino acid derivatives are the following N^{α} -

cocoyl ** - $\text{N}^{\alpha},\text{N}^{\beta}$ -dimethyl- α , γ -diaminobutyric acid methyl ester hydrochloride, N^{α} -lauroyl-L-ornithine methyl ester hydrochloride, N^{α} -lauroyl- $\text{N}^{\alpha},\text{N}^{\beta}$ -dimethylornithine benzyl ester hydrochloride, N^{α} -palmitoyl- $\text{N}^{\alpha},\text{N}^{\beta}$ -trimethylornithine methyl ester hydrochloride, N^{α} -lauroyl- N^{α} -benzyl- N^{α} -methyl ornithine methyl ester hydrochloride, $\text{N}^{\alpha},\text{N}^{\beta}$ -dimethyl- N^{α} -hydrogenated tallowyl ** ornithine ethyl ester hydrochloride, N^{α} -lauroylcitrulline methyl ester pyrrolidonecarboxylate, N^{α} -lauroyllysine methyl ester hydrochloride, N^{α} -myristoyllysine methyl ester hydrochloride, N^{α} -myristoyllysine amide hydrochloride, N^{α} -palmitoyl- $\text{N}^{\alpha},\text{N}^{\beta}$ -dimethyllysine methyl ester hydrochloride, N^{α} -lauroyl- N^{α} -benzyl- N^{α} -methyllysine methyl ester hydrochloride, N^{α} -cocoyl ** arginine ethyl ester pyrrolidonecarboxylate, N^{α} -cocoyl ** arginine methyl ester pyrrolidonecarboxylate, N^{α} -lauroylarginine methyl ester α -pyrrolidonecarboxylate, N^{α} -lauroylarginine methyl ester hydrochloride, N^{α} -stearoylarginine methyl ester hydrochloride, N -hydrogenated tallowyl ** arginine methyl ester hydrochloride, N -semihydrogenated tallowyl ** arginine butyl ester hydrochloride, N^{α} -lauroylhistidine methyl ester hydrochloride and so on. The abbreviations used herein are as follows: cocoyl ** , coconut oil fatty acid residue; hydrogenated tallowyl ** , hydrogenated beef tallow fatty acid residue; semihydrogenated tallowyl ** , semihydrogenated beef tallow fatty acid residue. Of course, the compounds which may be employed in the present invention are not limited thereto.

The first characteristic feature is a fact that the mono-N-higher aliphatic acyl basic amino acid derivatives show a good inhibitory effect against microorganisms which possess relatively strong resistance not only to gram positive bacterium, such as *Staphylococcus aureus* and *Bacillus subtilis*, but also to gram negative bacterium, such as *Pseudomonas aeruginosa*, *Escherichia coli* and *Proteus vulgaris*. The bactericidal or inhibitory effect of the compounds of the present invention in comparison with that of "Hyamine" (product of Rohm & Haas Co., Inc.) and hexachlorophene are illustrated in the Table 1. The phenol coefficient of N^{α} -cocoyl-L-arginic ethyl ester pyrrolidonecarboxylate shows high value. For example, that phenol coefficient toward *Escherichia coli*, *Pseudomonas aeruginosa* and *Staphylococcus aureus* is 170, 85 and 250 respectively.

NOTE.—The numerical value in table 1 indicates inhibiting concentration of compound against the growth of microorganism in $\gamma/\text{cc.}$, under contacting of each microorganism in those water solution for ten minutes.

The microorganisms, culture media and preparation of cultured cells employed in the test, and the assay method of bactericidal activity are as follows:

(a) Microorganisms employed:

1. *Escherichia coli* (ATCC 3655)
2. *Pseudomonas aeruginosa* (IAM 1002)
3. *Proteus vulgaris* (IAM 1025)
4. *Staphylococcus aureus* (ATCC 6538)
5. *Bacillus subtilis* (ATCC 6633)
6. *Candida albicans* (ATCC 10259)
7. *Aspergillus niger* (ATCC 9642)

(b) Culture media employed:

1. Meat extract 1.0%, polypeptone 1.0%, NaCl 0.25% pH 7.0 (used for microorganisms 1-5).
2. Yeast extract 0.3%, malt extract 0.3%, polypeptone 0.5%, glucose, 1.0%, pH 6.2 (used for microorganisms 6 and 7).

(c) Preparation of cultured cells: Microorganisms 1-6 were cultured statically at 31° C. for 20 to 24 hr. in test tubes into which are above-mentioned media were poured, while microorganism 7 was cultured at 31° C. for 4 days on the yeast-malt agar slant.

(d) Assay method of bactericidal activity: 0.5 ml. of the above-mentioned cultured cells was inoculated respectively to each test tube in which 10 ml. of sterilized water solution containing each concentration of various compounds was poured. After cells were contacted with the compound, one loopful of cell suspension of microorganismss 1 to 5 was spread on a nutrient-bouillon agar plate, while the yeast-malt agar plate was used in case of microorganisms 6 and 7. After cultivation at 31° C. for 48 hr., living or died of cells was judged.

The second characteristic feature in this invention is the fact that these non-N-higher aliphatic acyl basic amino acid derivatives possess a powerful antibacterial activity against microorganisms which possess relatively strong resistance to various known antiviral compounds, such as *Bacillus subtilis*, *Candida albicans* and *Aspergillus niger*. For example, the bacteriostatic or inhibitory effect of the compounds of the present invention in comparison with that of nitrofuran series compound, palmitoyl-L-lysyl-L-lysine methyl ester dihydrochloride, streptomycin, penicillin and sorbic acid lauroyl sarcosine are illustrated in the Table 2.

Number	Microorganism	Culture conditions	Time for precultivation, hours	Medium
10	1. <i>Escherichia coli</i> (ATCC 3655).	37° C., 3 days.	24	Nutrient-bouillon, pH 7.
	2. <i>Staphylococcus aureus</i> (ATCC 6538).	do	24	
	3. <i>Bacillus subtilis</i> (ATCC 6633).	do	24	
	4. <i>Pseudomonas aeruginosa</i> (IAM 1002).	30° C., 3 days.	24	
	5. <i>Candida albicans</i> (ATCC 10259).	25° C., 3 days.	24	
	6. <i>Aspergillus niger</i> (ATCC 9642).	do	24	

The third characteristic feature in this invention is the fact that they possess, only a small, or nontoxicity and do not cause any significant skin irritation. For example, in an acute oral toxicity test (LD_{50}) carried out on mice, the respective LD_{50} values of N^{α} -lauroyl-L-arginine methyl ester DL- α -pyrrolidone carboxylate and N^{α} -cocooyl-L-arginine ethyl ester pyrrolidone carboxylate are 2~3.0 g./kg., 10.75 g./kg. body weight. Accordingly, injuring to men and beasts are scarcely considered. Moreover, after this amino acid derivative was well mixed with polyethylene glycol, it was spread on the cloth of a sticking plaster for a patch test used in the wet state, and then applied to the skin for 24 hours. As the result of this patch test, almost no irritation against the skin was observed. And since this effective materials are water soluble cationic surface active agents, they have a remarkable detergent effect owing to strong foaming action.

Mono-N-higher aliphatic acyl basic amino acid derivatives or salts thereof can be used in any form of liquid, paste, powder, solid and etc. for the purpose of disinfection and sterilization in food sanitary field, environment public sanitary field, industrial field and farm and gardening field. As not only usual disinfectant agents but also toilet agents, deodorizer, rinsing agents for shampoo, detergents for vegetables and fruits and disinfectant agents for beasts they are also used.

Moreover, as they have strong emulsifying power toward cosmetics and are water-soluble, the solubility in

Figures in Tables represent the concentration ($\gamma/ml.$) of compounds which causes the growth inhibition of microorganisms.

Microorganisms tested, culture conditions and culture medium are as follows:

water phase, which is easily attacked by microorganisms, is higher than that in oil phase and they show appreciable antiseptic effect even when added in a small amount to cosmetics. And they possess strong penetrating power to a fiber. Accordingly, they may be applied to wide use.

The following shows the water solubilities of various mono-N-higher aliphatic acyl basic amino acid derivatives:

Compound:	Solubility (g./dl. 40° C.)	5

	20	

Mono-N-higher aliphatic acyl basic amino acid derivatives or salts thereof can be compounded, applied or sprayed according to the shape of soap, synthetic detergent, food, feed, cosmetics, fiber good, leather goods and paint in any form of liquid, powder, or emulsion.

In addition, we want to refer to a few following concrete use of the above-mentioned amino acid derivatives. Namely it was found that antiseptics comprising one or more than two kinds of these esters or salts as an effective component prevent brewage from "hiuchi putrefaction" rather completely.

The phenomenon of "hiuchi putrefaction" means that "sake" (Japanese wine), synthetic sake which contains partially brewing alcohol, or the products of brewing alcohol such as "mirin" (a sweet kind of "sake") becomes impossible to eat and drink because of white muddy and rancidity during the storage, or after the bottling.

Generally, "hiuchi putrefaction" is caused by *Lactobacillus heterohiochi*, *Lactobacillus japonicus* or *Lactobacillus homohiochi* which comes from brewage.

The example 9 and 10 indicate the antibacterial activity of N^a-lauroyl-L-arginine-methyl ester pyrrolidone carboxylate in comparison with salicylic acid which has been used habitually for prevention of "hiuchi putrefaction."

Moreover it is confirmed that these compounds adhered to a mucosa of oral cavity and were disinfectant in it for a long time. From these findings these compounds have marked antibacterial activity against both a bacterium belonging to genus *Lactobacillus*, a main pathogene of dental caries, and a bacterium belonging to genus *Staphylococcus*, a main pathogene of alveolar pyorrhea.

Table 3 shows the result of antibacterial test of these compounds against genus *Lactobacillus*, i.e., *Lactobacillus fermenti*-36 ATCC 9338, and *Streptococcus faecalis* ATCC 8083, and genus *Staphylococcus*, *Staphylococcus aureus* ATCC 65389.

As shown in Table 3, the antibacterial activity of generally used sodium N-lauroyl-sarcosinate was a control.

Sodium-N-lauroylsarcosinate	70	49	80

¹ The growth of *Lactobacillus* and *Streptococcus* was measured after 24 hr. standing culture at 37° C., and *Staphylococcus* was after 48 hr. at 31° C.

² Fatty acid residue of coconut oil.

³ DL-Pyrrolidone carboxylic acid.

Figures in Table 3 represent the concentration (γ /ml.) of compounds which causes the fifty percents inhibition of bacterial growth.

It is evident from the Table 3 that any of them is more effective than a control compound.

They possess nearly the same foaming power, which is a desirable surface active action as dentifrice, is the same as a control, sodium-N-lauroyl sarcosinate as shown in Table 4. The foaming power of 0 minute value are illustrated in the method of JISK 3362. As the results, above mentioned each compound possesses many extremely satisfactory properties as combining component of dentifrice.

Also, these active compounds are incorporated in soap or other synthetic detergents in 0.1-50% by weight, preferable 0.1-5% by weight based thereon. As synthetic detergents, for example, detergents containing predominantly at least one of N-higher acyl glutamate, N-higher acyl aspartate, alkylbenzenesulfonate, higher alkylsulfonate, α -olefin sulfonate and alkylethersulfate are taken. The shape of detergent may be bar, tablet, powder, paste or liquid according to the appearance of a product required.

In the appended drawing, FIGS. 1A to 1H diagrammatically illustrate the bacteriostatic effects of N^a-lauroyl-arginine methyl ester α -pyrrolidonecarboxylate of this invention against respective strains of microorganisms when added to culture media for the eight strains together with soap;

FIGS. 2A to 2D illustrate the bacteriostatic effects of the compound of FIGS. 1A to 1H in cooperation with a synthetic detergent when added to culture media of the strains illustrated in FIGS. 1A, 1C, 1E, and 1G respectively.

FIGS. 3A to 3C diagrammatically illustrate the bacteriostatic effects of a milled soap containing the same compound of the invention when added to culture media of the strains illustrated in FIGS. 1A, 1C, and 1G.

The drawing is explained in more detail in Examples 14, 15, and 16 hereinbelow.

EXAMPLE 1

Effect of 0.1% N^a-cocoyl-L-arginine ethyl ester-pyrrolidone carboxylate (CAE-P) on finger's disinfection and washing was examined.

Various kinds and numbers of bacteria were found to exist on the fingers of fifteen persons selected as a panel.

Each member immersed his hands and forearms by 35 cm. length from the tip of the middle finger in a wash-bowl containing 2 l. of tap water, and then repeated the same thing for a minute in 0.1% N^a-cocoyl-L-arginine ethyl ester pyrrolidone carboxylate solution. Finally he washed them in 2 l. of sterilized water.

The number of viable cells in these washings was counted after the performance of all members. On the other hand, in another group consisting of fifteen members the same experiment was carried out as control by using tap water instead of 0.1% N^a-cocoyl-L-arginine ethyl ester pyrrolidone carboxylate solution.

70		Number of viable cells (in 0.1 ml.)	
		Before washing	After washing
With 0.1% CAE-P		341	16
Without 0.1% CAE-P		348	289

EXAMPLE 2

The Bath Preparations were prepared by mixing such components as written in the following.

N ^a -cocoyl-L-arginine ethyl ester DL- α -pyrrolidone carboxylate	500	G. 5
Sodium iodide	1	50
Sodium bromide	0.6	55
Lithium carbonate	0.6	60
Manganese sulfate	0.01	65
Iron sulfate	0.01	70
Potassium chloride	15.0	75
Calcium chloride	40.0	80
Magnesium sulfate	66.4	85
Magnesium chloride	96.0	90
Sodium chloride	280.5	95

EXAMPLE 3

A Preventive Cleansing agent was prepared by mixing such components as shown in the following table.

Percent by weight		
N ^a -lauroyl-L-arginine ethyl ester DL- α -pyrrolidone carboxylate	3.0	20
Triethanol amine	2.0	25
Perfume	0.3	30
Water	94.7	35

EXAMPLE 4

The O/W type cold cream was prepared as follows.

Fifty grams of mineral oil, 7 g. of beeswax, 2 g. of "tween 40" (a registered trademark), 8 g. of "Atlas G-1726" (a registered trademark), were emulsified with 33 ml. of aqueous 1% N^a-myristoyl-N^a-dimethyl-L-lysine hydrochloride at 70° C.

On the other hand, the control cold cream containing 33 ml. of water was also prepared in the same way.

The newly prepared Cream Containing Lysine derivative caused a good emulsion and any change of the quality could not be found on storage at 30° C. and at moisture 90% during two months.

The control cream showed the growth of mold and resulted in coloration.

EXAMPLE 5

The toilet water was prepared as follows.

Ten part of Ethanol, 0.05 part of gum tragacanth, 5 part of propylene glycol, 1 part of N^a-lauroyl-L-arginine methyl ester-DL- α -pyrrolidone carboxylate were mixed with 85 part of water.

On the other hand, the control toilet water containing polyoxyethylene sorbitan monolaurate instead of arginine derivative was prepared in the same way.

In the newly prepared toilet water containing arginine derivative any change of the quality could not be found on storage at 30° C. and at the moisture 90% during one month in a room.

The control toilet water showed the growth of mold.

EXAMPLE 6

0.5 g. of N^a-parmitoyl-N^a-dimethyl-L-ornithine amide was mixed with 1 kg. of assorted feed.

In the newly prepared assorted feed containing ornithine derivative any change of the quality could not be found on storage at room temperature and during two weeks.

The control assorted feed showed the growth of mold and a putrid smell.

EXAMPLE 7

0.5 ml. of aqueous 3% N^a-lauroyl-L-arginine ethyl ester DL- α -pyrrolidone carboxylate was sprayed per 100 cm.² of surface of dressed oxhide.

In the sprayed dressed oxhide any change of the quality could not be found on storage at 30° C. and at moisture 90% during a month.

The control dressed oxhide showed the growth of mold.

EXAMPLE 8

The grams of N^aN^a-dimethyl N^a-lauroyl-DL-ornithine ethyl ester was dissolved homogeneously in 500 g. of water emulsion type paints consisting of 100 part of 50% vinyl chloride emulsion, 70 part of titanium white, 10 part of silicic anhydride, 190 part of calcium carbonate, 30 part of aqueous 10% polyvinyl alcohol, 1 part of ammonium polyacrylate, 1 part of "tween 40", and 100 part of water.

(i) In the newly prepared paint containing ornithine derivative any change of the quality could not be found on storage at 30° C. and at moisture 90% during three months in a room. The control paint occurred to phase separation by putrefaction.

(ii) Above paint was applied on the cedar board. In the film formed from the newly prepared paint containing ornithine derivative any change of the quality could not be found on storage at 30° C. and at moisture 90% during three months in a room. The control paint film showed the growth of mold.

EXAMPLE 9

An aqueous culture medium comprising 100 ml. of "sake" (Japanese wine) (16% alcohol concentration) and 0.8 g. of beef liver extract was adjusted to pH 5.0.

After sterilization, sample (N^a-lauroyl-L-arginine methyl ester pyrrolidone carboxylate) shown in Table 5 was added to the medium in the concentration of 1 γ /ml., 10 γ /ml. or 50 γ /ml. Three microorganisms of hiochi-bacteria listed in Table 5 were inoculated, and cultured at 30° C. Table 5 indicates the visible growth after 3 weeks culture in case of 10 and 50 γ /ml. Salicylic acid (LD₅₀ orally in rat: 0.9 g./kg.) was used as a control in the example.

TABLE 5

Concentration	Hiochi-bacteria						
	Lacto-bacillus-hetero-hiochii	Lacto-bacillus-japonicus	Lacto-bacillus-homo-hiochii	10 γ	50 γ	10 γ	50 γ
N ^a -lauroyl-L-arginine methylester pyrrolidone carboxylate	(1)	(1)	(2)	(1)	(2)	(1)	(2)
Salicylic acid	(2)	(2)	(2)	(2)	(2)	(2)	(2)

¹ Cell growth was not detected.

² Cell growth was clearly observed.

EXAMPLE 10

"Sake" A (17% as spirits) added with 0.001% of N^a-cocoyl-L-arginine ethyl ester pyrrolidone carboxylate and "Sake" B (17% as spirits) added with 0.001% of Na-salicylate were stored at 30° C. $\pm$ 2° C., and the flavor and taste were compared each other.

"Sake" A did not turn sour at all even after six months, while "Sake" B began to turn sour virtually after a month.

EXAMPLE 11

Kamaboko was prepared according to a known method by employing the following components; 70.0% of frozen fish meat, 2.6% of sodium chloride, 0.3% of "HI-ME" (Product of Ajinomoto Co., Inc., Mixture of sodium inosinate and sodium glutamate), 5.5% of egg albumin, 2.1% of sucrose, 13.8% of starch and 7.0% of cold water.

"Kamaboko" A added with 0.012% of L-citrulline methyl ester hydrochloride together with 0.012% of "AF-2" (Veno Pharmaceutical Co., Nitrofuran compounds) and "Kamaboko" B added with only 0.012% of "AF-2" were stored at 30° C. for 3 days in a petri dish with a cover. The result was that colonies of fungi conceived as Penicillium occurred on the "Kamaboko" B. However, any spoilage with bacterial slime or infection with fungi was not detected on the "Kamaboko" A in addition to no change in taste.

11
EXAMPLE 12

	Percent by weight
Dicalcium phosphate 2H ₂ O	44.5
Gum tragancanth	2.0
Glycerol	18.5
N ^a -cocooyl-L-arginine ethyl ester DL- α -pyrrolidone carboxylate	3.0
Saccharin	0.4
Flavoring material	1.0
Water	30.6

EXAMPLE 13

The wet dentifrice was prepared by mixing such components as shown in the following table.

	Percent by weight
Calcium carbonate precipitate	70.2
Sodium carboxymethyl cellulose	22.0
N ^a -lauroyl-L-arginine methyl ester DL- α -pyrrolidone carboxylate	3.0
Saccharin	0.5
Flavoring material	1.3
Water	3.0

EXAMPLE 14

N^a-Lauroyl - L - arginine methyl ester DL- α -pyrrolidone-carboxylate (referred to as DL-I) was added to 2.0 g. of fatty acid soap material in an amount given in Table 6 and the mixture was dissolved in 100 ml. of the culture medium shown in Table 7, and then was adjusted to a pH of between 6.2 and 7.3. 4 ml. of the respective solutions was inoculated with each of the eight kinds of microorganisms shown in Table 2 and cultivated under the condition shown in Table 2. The growth of microorganisms was estimated by increased turbidity of the culture solution and was verified by measuring at times absorbance (optical density) at 560 m μ with a spectrophotometer. The results were as shown in FIG. 1 from which the culture mediums (Nos. 4 and 5) added with DL-I were recognized to exhibit marked inhibitory effect to the growth of microorganisms as compared with the culture medium alone (No. 1) and with the culture medium (No. 2) added with fatty acid soap material alone, and also their inhibitory effect was recognized to be approximately equal with that of hexachlorophene.

TABLE 6

Number	Amount of soap material (g.)	Type and amount of deodorizer
Control:		
1	None	None.
2	2.0	Do.
3	2.0	G-11 ¹ 0.041 g.
The present invention:		
4	2.0	DL-I 0.039 g.
5	2.0	DL-I 0.025 g.

¹ G-11: hexachlorophene.

TABLE 7

Microorganism ¹	Cultivation temperature, °C.	Culture medium ²	pH of culture medium	Cultivation

EXAMPLE 15

N^a-Lauroyl - L - (or DL) - arginine methyl ester L- α -pyrrolidone-carboxylate (referred to as L-I or DL-I respectively) was added to 2 g. of monosodium N-cocooyl-L-(or DL)-glutamate (referred to as L-II or DL-II respectively) in an amount given in Table 8. Subsequently, inhibitory tests against various microorganisms were carried out according to the similar manner in Example 14.

TABLE 8

	Grams	Type and amount of deodorizer
30 Control:		
1.----- Soap material-----	2	None.
2.----- DL-II-----	2	Do.
3.----- DL-II-----	2	G-11 ¹ 0.041 g.
The present invention:		
4.----- DL-II-----	2	L-1 0.040 g.
5.----- L-II-----	2	DL-I 0.224 g.

¹ G-11: hexachlorophene.

Each of the culture media was recognized to exhibit a marked inhibitory effect against A-H microorganisms. 40 The results of inhibitory tests against A, C, E and G microorganisms were shown in FIG. 2. It can be seen from FIG. 2 that even the culture medium (No. 2) added with DL-II alone exhibits some extent of antibacterial activity compared with the culture medium alone (No. 1) but the culture media (Nos. 4 and 5) added with further L-I or DL-I exhibit more excellent antibacterial activity, that is comparable to hexachlorophene.

EXAMPLE 16

50 2 Parts of N^a-lauroyl - DL - arginine methyl ester L- α -pyrrolidone carboxylate (referred to as DL-I) was sufficiently compounded with 100 parts of soap material with a small roller. The mixture was warmed to 50-60° C. and extruded into a bar of soap having 25 mm. in diameter with a prodder for making soap and then moulded in a metal mould installed to an impact type moulding machine. The appearance of the bar soap thus prepared was equal with that of the bar soap prepared similarly from soap material alone. Also, there is recognized no difference between both the products in solubility by rubbing which was measured according to the Japanese Industrial Standards M-3304, and in disintegration in water.

60 Next, 2.0 g. of each of samples was scraped from the respective products, i.e., the bar soap added with DL-I and one added with no DL-I, and dissolved respectively in 100 ml. of culture solution as in the Example 14. 4 ml. of the solution was inoculated with the microorganisms shown in Table 2 and cultivated under the same conditions. The growth of microorganisms was estimated from the turbidity of the culture solution, which was measured using a spectrophotometer according to the similar manner as in Example 14.

65 As the result, the culture medium added with DL-I was recognized to exhibit an inhibitory effect against all of the A-H strains. Only the results of inhibitory test to the

70

A, C and G strains were shown in FIG. 3 wherein a dotted line ···· means the case where DL-I was added and a line — means the case where DL-I was not added. It may be seen that the soap containing DL-I is effective in inhibiting the growth of microorganisms as compared with the soap not containing DL-I and especially it exhibits a marked inhibitory effect against A micro-organism.

EXAMPLE 17

10 Parts of sodium sulfate was mixed with 90 parts of sodium dodecyl sulfate (referred to as SDS) and N^a -lauroyl- N^b , N^b -dimethyl-DL-ornithine methyl ester lactate (referred to as DL-III) was added thereto in an amount given in Table 9 to prepare shampoo composition. Each sample was dissolved in 100 ml. of the culture medium shown in Table 6 and 4 ml. of the solution was inoculated with each one of A-H microorganisms and cultivated. Subsequently, the growth of microorganisms was measured according to the similar manner as in Example 1. As the results, in case of the culture medium (No. 1) not added with DL-III, symptom of the growth of microorganisms was recognized in one hour after cultivation, while the culture medium (Nos. 4 and 5) added with DL-III was recognized to inhibit the growth of microorganisms for 10-25 hours after cultivation. This was approximately equal to the inhibitory effect of the culture medium (No. 2) added with hexachlorophene.

TABLE 9

Number	Amount of SDS, g.	Amount of Na_2SO_4 , g.	Type and amount of deodorizer
1	1.8	0.2	None.
2	1.8	0.2	$G-11^1 0.040$ g.
3	1.8	0.2	DL-III 0.041 g.
4	1.8	0.2	DL-III 0.225 g.

¹ G-11: hexachlorophene.

EXAMPLE 18

5 Parts of each of the eleven kinds of mono N -higher aliphatic acyl basic amino acid derivatives shown in Table 10 was sufficiently compounded together with 100 parts of soap material and with 1-3 parts of water using a roller. The mixture was warmed to 50-55° C. and extended into a bar soap having 25 mm. in diameter using a prodder, and the bar soap was stamped.

The result of having measured the solubility by rubbing according to the Japanese Industrial Standards K-3304 on the bar soap prepared in the above and the bar soap similarly prepared from soap material alone showed that any of the bar soaps containing the compounds of the present invention has a value within 20% from the measured value of the bar soap of control. Also, there was no appreciable difference between both the products in disintegration in water.

TABLE 10

1. N^a -Myristoyl-L-lysine methyl ester hydrochloride
2. N^a -Myristoyl-L-lysine amide hydrochloride
3. N^a -Palmitoyl- N^a , N^b - dimethyl-L-lysine methyl ester hydrochloride
4. N^a - Lauroyl- N^a , N^b , N^b -trimethyl-DL-ornithine methyl ester hydrochloride
5. N^a -cocoyl- N^a -methyl-DL-ornithine methyl ester hydrochloride
6. N^a -Palmitoyl- N^a , N^b -dimethyl - DL - ornithine benzyl-ester hydrochloride
7. N^a -Lauroyl- N^a -benzyl- N^b -methyl-DL-ornithine methyl ester hydrochloride
8. N^a -cocoyl- N^a , N^b -dimethyl - DL - α , γ -diaminobutyric acid methyl ester hydrochloride
9. N^a , N^b -dimethyl- N^a -hydrogenated tallowyl - DL - ornithine ethyl ester hydrochloride
10. N^a -hydrogenated tallowyl arginine methyl ester L- α -pyrrolidone carboxylate
11. N^a -semihydrogenated tallowyl arginine butyl ester hydrochloride

2 g. of the each sample was scraped from the respective bar soaps containing the above compounds and the bar soap for control, and dissolved in 100 ml. of culture mediums shown in Table 6. 4 ml. of the each solution was inoculated with each microorganism of A and E micro-organisms and cultivated. The growth of the micro-organisms was estimated from the turbidity of the culture solution according to Example 14. As the result of carrying out the standing cultivation for 22 hours with respect to A microorganism, the absorbance of the culture solution added with the bar soap for control in 10 hours after cultivation was 0.80, while the absorbance of any culture solutions added with the bar soaps containing the additives in the that time was below 0.10. Also, as the result of carrying out the shaking cultivation for 12 hours with respect to E microorganism, the absorbance of the culture solution added with the bar soap for control in 8-10 hours after cultivation was 0.20, while that of any culture solutions added with the bar soaps containing the additives in that time was 0.05. As apparent from these results. Mono- N -higher aliphatic acyl basic amino acid derivatives were recognized to exhibit deodorant effect.

SUPPLEMENTAL EXAMPLE

(i) Preparation of N^a -lauroyl-L-lysine methyl ester hydrochloride

66.2 g. (0.2 m.) of N^a -carbobenzoyl-L-lysine methyl ester hydrochloride were dissolved in 200 ml. of tetrahydrofuran and then added with 58.5 ml. (0.42 m.) of triethylamine and 43.7 g. (0.2 m.) of lauroyl chloride under stirring and cooling. The resulted mixture was allowed to stand overnight at room temperature. The resulting reaction mixture was neutralized with 800 ml. of 1N HCl.

The precipitate was filtered and it was dissolved in 400 ml. of ethanol. The ethanol solution was added slowly into 800 ml. of aqueous ammonia under cooled to 0° C. The precipitate of separates out was filtered and dried.

The thus obtained 59.8 g. of N^a -lauryl- N^a -carbobenzoyl-L-lysine methyl ester were dissolved in 600 ml. of ethanol and then with 12.7 ml. of conc. hydrochloric acid and 23 g. of 10% palladium-carbon. Thereafter, the reaction solution was reduced by hydrogen under stirring and atmospheric pressure. The catalyst was filtered off. The reaction mixture concentrated under reduced pressure to remove solvent and water completely. The residue were dissolved in methanol and then added with ethyl acetate. Whereby white crystals were precipitated and filtered out. The crude crystals were recrystallized from ethanol and ethyl acetate to obtain 13.3 g. of the purified product of N^a -lauroyl-L-lysine methyl ester hydrochloride. Yield: 88.0%, m.p. 96-98° C.

(ii) Preparation of N^a -cocoyl-L-arginine ethyl ester DL- α -pyrrolidone carboxylate

35.0 g. (0.2 m.) of L-arginine were dissolved in 200 ml. of acetone and 150 ml. of water and then added drop-wise under cooled to 10-20° C., stirring and adjusting to pH 11.5-12.0 with 8N sodium hydroxide and 40 g. (0.18 m.) of cocoyl chloride (coconut oil fatty acid chloride). The reaction mixture was neutralized with 6 N HCl to pH 5.0 and it was added into 300 ml. of cold water.

The precipitate of separates out, was filtered and dried, 0.5 g. of crude crystalline N^a -cocoyl-L-arginine was obtained. Yield: 77.9%, m.p. 230-235° C.

35.6 g. (0.1 m.) of above compound was saturated with 200 ml. of ethanol solution containing hydrogen chloride and allowed to stand overnight at room temperature. The insoluble material of resulting reaction mixture in filtered off. The filtrate was concentrated under reduced pressure. The residue was dissolved in 200 ml. of ethyl acetate and then added with triethyl amine under cooling. Organic solvent layer was washed with water and then added with

12.9 g. of DL- α -pyrrolidone carboxylic acid under heating at 30° C. Theerafter, the reaction mixture was filtered to remove a small amount of insoluble material. The filtrate was concentrated under reduced pressure. The residue was recrystallized from ethanol. 12.4 g. of white crystal of Na α -cocooyl-L-arginine ethyl ester DL- α -pyrrolidone carboxylate was obtained. m.p. 181-184° C. (dec.).

What we claim is:

1. A compound which is the lower alkyl or benzyl ester of an N-monoacyl derivative of arginine or of the 10 N α -methyl or N α -benzyl derivative of said arginine, or a water soluble salt of said ester with hydrochloric acid, sulfuric acid, α -pyrrolidonecarboxylic acid, glutamic acid, aspartic acid, lactic acid, citric acid, or acetic acid, said ester having the formula

wherein R-CO is the acyl radical of a fatty acid having 20 6 to 20 carbon atoms, R₁ is hydrogen, methyl or benzyl, and X is lower alkoxy having up to four carbon atoms or benzyloxy.

2. A compound as set forth in claim 1 which is an ester of N-monoacyl arginine or a salt of said ester.

3. A compound as set forth in claim 2, wherein acyl is lauroyl.

4. A compound as set forth in claim 3 wherein said ester is a lower alkyl ester of N-lauroyl arginine.

5. A compound as set forth in claim 4, wherein said compound is a salt of a lower alkyl ester of N-lauroyl arginine with hydrochloric acid or α -pyrrolidonecarboxylic acid.

6. N α -Lauroylarginine ethyl ester α -pyrrolidonecarboxylate.
